UNITED STATES PATENT OFFICE

161,341

FLOWER HOLDER OR SIMILAR ARTICLE

Howard H. Isard, Bell, Calif.

Application February 7, 1950, Serial No. 7,783

Term of patent 3½ years

(Cl. D35—3)

To all whom it may concern:

Be it known that I, Howard H. Isard, a citizen of the United States, residing in Bell, in the county of Los Angeles, and State of California, have invented a new, original, and ornamental Design for a Flower Holder or Similar Article, of which the following is a specification, reference being had to the accompanying drawing, forming part thereof:

Fig. 1 is a perspective view of a flower holder or similar article, showing my new design.

Fig. 2 is a top plan view thereof.

I claim:

The ornamental design for a flower holder or similar article, substantially as shown.

HOWARD H. ISARD.
